UNITED STATES PATENT OFFICE.

FRED C. HOWE, OF NEW HAVEN, CONNECTICUT.

LAMP.

1,147,727.

Specification of Letters Patent. Patented July 27, 1915.

Application filed September 17, 1914. Serial No. 862,184.

To all whom it may concern:

Be it known that I, FRED C. HOWE, a citizen of the United States of America, residing in the city and county of New Haven, 5 State of Connecticut, have invented certain new and useful Improvements in Lamps, of which the following is a specification.

This invention relates to a utility lamp, especially adapted to be carried upon automobiles, motor-boats, and the like, and aims 10 to provide improvements therein.

The present invention provides a lamp which is adapted to be turned so as to direct its rays in any and all directions, as 15 over the earth or sea, or sky, for searching out objects, or be directed upon parts of the vehicle and its vicinity for making examinations or repairs.

The invention further provides a device 20 which can be manipulated by a handle within the convenient reach of the operator of the vehicle, and which can be manipulated by a simple rotary movement of the handle, or combination of such movements.

Other features of advantage and importance will be hereinafter set out.

An embodiment of the invention is illustrated in the accompanying drawings, wherein—

Figure 1 illustrates the improved lamp applied to an automobile; Fig. 2 is a side elevation of the device, with parts in section; Fig. 3 is a top plan view of the device; Fig. 4 is a longitudinal section of the handle-end of the device, and showing the manipulation of the device; Fig. 5 is a front view; Fig. 6 is a section on line 6—6, Fig. 2; and Fig. 7 is a section on line 7—7, Fig. 2.

Referring to said drawings, numeral 1 40 designates a lamp of any suitable kind or construction, and 2 its base or support. The lamp support is preferably in the form of an arm or bracket 3, carried upon a sleeve 4 swiveled in a suitable bracket 5, by which 45 it may be attached to the automobile body or other structure to which the lamp is applied. The lamp is swiveled upon the arm 3, as at 6, and is preferably adapted to turn through an angle or arc of 360 degrees.

The swiveling of the lamp support or base is 50 preferably such that it also may be turned through an arc or angle of 360 degrees in a plane at right angles to the axis of the lamp. A handle 7, which is conveniently 55 accessible to the operator in his seat, is provided for turning the lamp, and also the

lamp base or support 2. The handle operates upon the lamp through a shaft 8 and a suitable transmission such as miter-gears 9, fixed upon the shaft 8, and 10, on the axis of the lamp. The handle 7 operates upon the lamp support through a suitable clutch 11, which may be conveniently formed by interengaging teeth or projections on the end of a projection or prolongation 12 of the sleeve 4, and on the end of a tubular projection 13 from the handle. The handle preferably slides upon the shaft 8 in such manner as to bring the clutch teeth thereon into and out of engagement with the clutch teeth on the part 12 of the lamp support. When the handle turns the lamp support 2, the pinion 9 is turned to the same degree so that the lamp is not turned on its axis during the turning of the lamp support. To prevent turning of the handle 7 on the shaft 8 the end 14 of the shaft 8 may be square, and the handle and the base of the tubular extension 13 may be provided with a corresponding square recess 15. A spring 16, bearing at one end against the handle and at its other end against a collar 17 on the shaft 8, normally pushes said handle out of clutching engagement with the lamp support 2. A friction device, such as 80 a split cupped washer 18, bearing against a shoulder on the sleeve 4, is preferably provided for restraining turning of the lamp support in the bracket 7. Means are also 85 preferably provided for locking the lamp support and shaft 8 in one or more positions thereof, such means being a spring 90 pressed finger-piece 19 having a projection 20 thereon adapted to enter slots 21, 22 in the sleeve extension 12 and the shaft 8 respectively. A casing 23 may be provided 95 for the gears, and a weight 24 may be provided for counterbalancing the lamp 1.

Operation: The lamp being in the position shown in Fig. 2 can be turned on its axis so as to direct its beam in any direction within a radius of 360 degrees (Fig. 3) by pressing upon the finger-piece 19, so as to lift the projection 20 therefrom from the slot 22 in the shaft 8 (but preferably not 100 from the slot 21 in the sleeve extension 12), and turning the handle 7. When it is desired to direct the light upon a spot in another plane than that in which the lamp is shown in Fig. 2, the finger-piece 19 is 105 pressed so as to withdraw the projection 20 from both slots 21 and 22, the handle 7 is 110

2

pushed inward, against the tension of the spring 16, into clutching engagement with the sleeve extension 12 of the lamp support 2, and the handle turned so as to move the 5 lamp support through a suitable angle or arc, as indicated in Fig. 5. The spring is then allowed to press the handle out of clutching engagement, and by then turning the handle the lamp can be swung through 10 an arc of 360 degrees in the new plane. The lamp support being movable to any and all degrees within a circle, and the lamp being movable on its base or support to any degree within a circle, it is possible 15 to direct the beam of light in any and all directions, and upon substantially any desired object.

The invention may receive other mechanical expressions than those herein illustrated and specifically described.

What is claimed is:—

1. A device of the character described, comprising a lamp, a pivoted support for said lamp, said lamp being pivoted on its 25 support, a handle for moving said support and said lamp on their pivots, and a clutch between said handle and support.

2. A device of the character described, comprising a lamp, a pivoted support for 30 said lamp, said lamp being pivoted on its support, a shaft adapted to turn said lamp on its pivot, a handle for turning said shaft, and a clutch between said handle and support, whereby said handle may also turn 35 said support.

3. A device of the character described, comprising a lamp, a pivoted support for said lamp, said lamp being pivoted on its support, a handle for moving said support 40 and said lamp on their pivots, and a single means for locking said lamp and support against movement.

4. A device of the character described, comprising a lamp, a pivoted support for 45 said lamp, said lamp being pivoted on its support, a handle for moving said support

and said lamp on their pivots, and a single means adapted to lock said lamp and support against movement, said means being also adapted to lock said support independently of said lamp. 50

5. A device of the character described, comprising a lamp, a pivoted support for said lamp, said lamp being pivoted on its support, a shaft adapted to turn said lamp on its pivot, a handle for turning said shaft, and a clutch between said handle and support, whereby said handle may also turn 55 said support, said handle being slidable on said shaft for clutching said support. 60

6. A device of the character described comprising a lamp, a lamp-support, said lamp-support being pivotally mounted and said lamp being pivotally mounted on said support, a shaft for actuating said lamp and 65 a shaft for actuating said lamp-support, said shafts being coaxial, and a handle for operating said shafts, said handle being in constant operative connection with said lamp actuating shaft, and being adapted to 70 to be moved into and out of operative connection with said lamp-support actuating shaft.

7. A device of the character described comprising a lamp, a support for said lamp, 75 a pivot on which said lamp is mounted, an operating shaft for turning said lamp, and a pair of bevel gears, one on said pivot and the other on said shaft, adapted to transmit motion from said operating shaft to 80 said lamp, said support also being pivoted, and a shaft for turning said support, said support operating shaft being coaxial with said lamp operating shaft.

In witness whereof, I have hereunto signed 85 my name in the presence of two subscribing witnesses.

FRED C. HOWE.

DISCLAIMER.

1,147,727.—*Fred C. Howe*, New Haven, Conn. LAMPS. Patent dated July 27, 1915.
Disclaimer filed February 5, 1926, by the assignee, *Albert I. Appleton*.

Hereby enters this disclaimer and disclaims from the scope of claim 7 of said Patent No. 1,147,727 any lamp in which said "support-operating shaft" moves angularly about any other axis than its long axis for the purpose of turning the support for the lamp.
